DRILLING TOOL AND DETACHABLE BIT

Application filed February 12, 1929. Serial No. 339,411.

This invention relates to improvements in drills, and more particularly to a combination drill tool and detachable bit.

In combination, drilling tools and bits which are detachable, have been employed heretofore with but mediocre success due particularly to insufficient and impractical means for securing the bit to the tool.

The principal object of this invention is to provide a combination tool and bit construction wherein the bit may be firmly secured to the tool and yet be capable of quick detachment.

Another object of importance, is to provide means, whereby the individual cutting elements of a fishtail type bit may be readily replaced.

Other objects and advantages of the invention will become apparent as the same is better understood from the following description and claim.

In the drawings:

Figure 1 represents a fragmentary side elevation of the improved structure.

Fig. 2 is a fragmentary side elevation looking at the structure from a position at right angles to the structure as appears in Fig. 1.

Fig. 3 is a fragmentary longitudinal sectional view through the drilling tool with the bit removed.

Fig. 4 is an end elevation of the bit holding end of the tool.

Fig. 5 is a side elevation of one of the bit elements.

Referring to the drawings wherein like numerals designate like parts, the drilling tool or screw 3 is shown abruptly severed transversely in the manner designated by the numeral 4. The present improved structure is in the nature of a fishtail type of drill and is provided with a pair of detachable bit elements 5—5, in substitution of the usual cutting blades integral to the tool in conventional drills.

The transversely severed end of the tool 3, is bifurcated, as at 6. Each furcation is provided with an undercut channel 7, and these channels extend longitudinally of the tool 3 and are slightly tapered inwardly. Each

furcation at the bottom of its groove 7 is provided with a boss 8 adjacent its outer end.

Each bit 5 is constructed of springy metal and is curved in the usual manner and sharpened at one end in the manner denoted by 9. The opposite end portion of each bit element has its longitudinal edge portion beveled as denoted by the numeral 10, this end portion of the element being also slightly tapered. Each element is also provided with a recess 11 at a point inwardly from said tapered end portion.

The bits are adapted for engagement with in the channels in the manner shown in Figs. 1 and 2. The bosses 8 spring into the recess 11 to firmly retain the bit in wedged connection to the tool.

Obviously, in the construction of the novel structure, certain changes may be resorted to without departing from the spirit and scope of the invention as claimed hereinafter.

Having thus described our invention, what we claim as new is:—

In combination, a drilling tool provided with a dove-tail groove in the free end thereof, a cutting bit of spring material provided with beveled edges for engagement within the said dove-tailed groove, said spring bit being provided with a recess, and a boss on the bit for engagement within the said recess.

In testimony whereof we affix our signatures.

ELZADORE S. McCULLOUGH.
